UNITED STATES PATENT OFFICE.

MASON P. RUMNEY, OF DETROIT, MICHIGAN, ASSIGNOR TO DETROIT STEEL PRODUCTS COMPANY, OF DETROIT, MICHIGAN, A CORPORATION OF MICHIGAN.

WINDOW CONSTRUCTION.

Application filed September 14, 1925. Serial No. 56,357.

This invention relates to windows and the like, and more particularly to improvements in the structural details of devices of this general character.

5 The invention has as an object to provide improved means for uniting certain parts of the window construction; to provide simple but efficient means for bracing or reinforcing the frame of the window; and to provide means for relatively and outwardly adjusting the sash and frame of the window.

10 The invention has also as its objects to simplify, render more efficient, and improve generally constructions of this character, and to 15 provide means for relatively and outwardly adjusting the sash and frame of the window.

15 The invention consists in the novel construction and arrangement of parts more fully described in the accompanying specification and illustrated in the drawings; wherein

20 Figure 1 is a front elevation, partly broken away, of a conventional form of window with my invention associated therewith;

25 Figure 2 is an enlarged vertical section, partly broken away, taken substantially on the plane indicated by the line 2—2 in Figure 1;

Figure 3 is a horizontal detailed sectional view taken substantially on the plane indicated by the line 3—3 in Figure 2;

30 Figure 4 is a detailed sectional view taken substantially on the plane indicated by the line 4—4 in Figure 2;

Figure 5 is a detailed sectional view taken substantially on the plane indicated by the line 5—5 in Figure 3;

35 Figure 6 is a fragmentary perspective view of one corner of the window construction;

Figure 7 is a similar view seen from a different angle; and

40 Figure 8 is a fragmentary perspective view showing the construction of the upper pivot pin.

Referring now particularly to the drawings wherein like reference characters indicate like parts, it will be noted that there is 45 illustrated a frame 10 formed preferably of angle bars provided with spaced flanges 11, and an intermediate web portion 12. The swinging unit or sash 13 formed also of angle bars is provided with flange portions 14 abutting the flanges 11 on the frame, thereby affording a double contact throughout, whereby a weatherproof joint is produced. While angle bars of cross sectional shapes substantially as herein shown and described have 50 been found to be entirely satisfactory and de-

sirable it will be obvious as this description proceeds that the objects of this invention may be accomplished equally as well in a construction wherein the sash and frame have other cross sectional shapes.

60

In the construction illustrated herein the swinging unit or sash 13 is adapted to swing horizontally away from the frame and is mounted upon a pair of vertically aligned pivots arranged at one side of the sash. As 65 the construction of these two pivots or hinge members is substantially identical a description in detail of one together with a reference to the slight differences will suffice.

65

The reference character 15 is applied to 70 one of the hinge parts here shown as an angle bracket consisting of a vertically extending side 16 and a horizontally arranged side 17 arranged at right angles to the side 16. For 75 permanently uniting the hinge part 15 with the frame 10 the frame is provided with a longitudinally extending slot or opening 18 through which the reduced end 19 of the hinge part 15 is adapted to extend. The protruding portion 19 of the hinge part 15 is 80 preferably reduced as shown and described so as to produce a shoulder 20 adapted to engage the face of flange 11 of the frame. A 85 filler or spacing block 21 is preferably arranged between the portion 19 of the hinge part and the web 12 of the frame whereby the parts are secured together by means of rivets 22 or the like. These rivets pass through the portion 19 of the hinge part, through filler block 21 and web 12 of the frame.

90

The parts are additionally secured together by welding the same as indicated at 23, preferably at the point where the hinge part 15 passes through aperture 18.

The horizontally arranged portion 17 of 95 the hinge part abuts flange 11 of the frame as shown at 24, and is preferably welded thereto as indicated at 25. Thus the brackets 15 are rigidly connected to and become a part of the frame 10. Secured to the corresponding corner of the sash or swinging unit 13 is a bracket 26 substantially L-shaped, with the arms thereof riveted to flange 14 of the sash as indicated at 27. With the bracket 26 arranged at the corner of the sash the arms 100 thereof extend parallel with and adjacent to the vertical and horizontal portions 13^a and 13^b respectively of the sash thereby reinforcing the sash at the point of connection between the upright and horizontal sides there- 105 110

of. Extending outwardly from the bracket 26 is an arm 28 preferably formed with an enlarged end portion or boss 29 for the reception of the pivot pins 31 or 31^a. The member 5 constituted by the parts 26, 28, and 29 comprises the second hinge part companion to hinge part 15.

The pin 31 of the lower hinge is preferably driven from below into a recess in the boss 29.

10 The boss 29 of upper arm 28 is centrally apertured as at 30 for the reception of pivot pin 31^a and is preferably provided with a threaded aperture for the reception of a set screw 38, which engages a groove 38^a in upper pivot pin 15 31^a for holding this pin in place. It will be noted that this upper pivot pin is preferably headed as shown at 39 and extends entirely through boss 29 and is removable when released by set screw 38.

20 The horizontal portion 17 of hinge part 15 is apertured as at 32 for the reception of a bushing 33 provided with an irregular-shaped head 34 and threaded as at 35 for engagement with the clamping nut 36. By 25 means of the head 34 it is possible to rotate the bushing 33 relatively to the opening 32 in hinge part 15, the bushing 33 being clamped in its several positions of rotative adjustment by means of the clamping nut 36.

30 The bushing 33 is formed with an eccentrically arranged bore or opening 37 through which the pivot pin 31 is adapted to pass. By reason of the eccentricity of the aperture 37 with reference to the longitudinal center 35 of the bushing 33 the pivot pin 31 and consequently the hinge part secured to the sash may be adjusted with reference to hinge part 15 so as to provide for a relative adjustment between the sash and the frame. Consequently 40 after assembling the parts of the window inaccuracies in the frame and sash construction may be compensated for thereby making possible the weatherproof joint therebetween.

In windows of this general construction it 45 is customary to glaze the same with the glass 40 abutting the inwardly extending flange 41 as clearly shown. By making one pivot pin, here shown as the upper pin 31^a, removable, the swinging unit or sash 13 may be removed 50 for glazing, etc. Furthermore, as was here-

tofore mentioned, the hinge parts or brackets 15 are permanently attached to the frame 13 and for all practical purposes become parts thereof. The brackets 15 are formed preferably of rolled steel or the like and the sides 55 16 and 17 thereof project beyond the planes of the other hinge part which is ordinarily of cast metal and softer, thereby affording a measure of protection for this latter part both in shipment and in practice. 60

From the foregoing it will be apparent that the described construction contemplates first; a particularly effective and rigid connection between one of the hinge parts and the frame, accomplished by welding and riveting the shouldered hinge part to the frame; second; a reinforcing bracket for reinforcing the connection between adjacent sash sections, this bracket constituting a portion of the second hinge part; and lastly a compensating pivotal connection between the hinge parts whereby adjustment between the sash and frame is possible. 65

70 While an embodiment of the invention has been described and illustrated in some detail it will be immediately apparent to those skilled in this particular art that various changes and modifications may be resorted to without departing from the spirit and scope of the invention and to this end reservation is 75 made to make such changes as may come within the purview of the accompanying claim.

What I claim as my invention is:—

A hinge for windows or the like including a hinge part consisting of a vertically extending side and a horizontally arranged side provided with an opening, a bushing journaled in said opening having an eccentrically arranged opening, a second hinge part provided with a boss, means for adjustably connecting the second hinge part to the first mentioned hinge part including a pivot pin secured in said boss and engaging the opening in said bushing, and means for clamping said second hinge part in its several positions of rotative adjustment including a member threadedly engaging the lower end of said bushing. 90 95

In testimony whereof I affix my signature.

MASON P. RUMNEY.
